UNITED STATES PATENT OFFICE

GEORGE M. JACKSON, OF CHICAGO, ILLINOIS, ASSIGNOR TO THE WESTERN SHADE CLOTH COMPANY, OF CHICAGO, ILLINOIS, A CORPORATION OF ILLINOIS

TWO-TONE WINDOW SHADE CLOTH AND PROCESS OF MANUFACTURE

Application filed March 21, 1929. Serial No. 348,758.

This invention relates to a two-tone window shade cloth and process of manufacture, and has for one of its principal objects the provision of an embossed window shade cloth which has a two-color tone effect when viewed against light passing therethrough.

One of the important objects of this invention is to provide an embossed and translucent window shade cloth having a varying colored pattern brought into relief by having certain portions thereof embossed or raised above the general surface level while certain other portions are below the general surface level, these being filled to varying degrees with coloring material, coating, size, or the like, whereby the varying transmitted light effects are produced.

Still another and further important object of this invention is to provide in a window shade cloth various ornamental patterns which are made to stand out by embossing and later filling in of certain of the embossed lines whereby a practically infinite variety of patterns and color combinations may be produced.

Other and further important objects of the invention will be apparent from the disclosures in the accompanying drawings and following specification.

The invention, in a preferred form, is illustrated in the drawings and hereinafter more fully described.

In the drawings:

Figure 1 is a plan view of a piece of embossed window shade cloth having a color pattern of various tone effects.

Figure 2 is a sectional view taken along any representative line of Figure 1.

Figure 3 is a diagrammatic view illustrating the preferred process of manufacture of this improved shade cloth.

As shown in the drawings:

The reference numeral 10 indicates generally a portion of a sheet of window shade cloth formed of the usual materials, namely cotton cloth or the like, having applied thereto a plurality of coats of filler or size which for the purpose of this invention is of a composition so as to render the cloth pliable to a certain degree, and accordingly able to re-

ceive and retain impressions from an embossing roll or the like. This composition may also be of such material as to render the shade cloth itself waterproof, and accordingly washable.

The cloth after having been preliminarily coated or filled is embossed in any usual or convenient manner by passing through embossing rollers, the design or pattern including score lines set at various angles to the edge of the cloth as illustrated at 12, 14, and 16 in Figure 1.

The coating or filling applied to the cloth before processing is preferably of a white or neutral color, and after the embossing has been accomplished, the cloth is given a final coating of any desired color, this coating material being illustrated at 18 in Figure 3, the cloth at the time being passed over a table or the like 20 by means of feed rollers 22, and with its surface in contact with the lower edge of a doctor knife or the like 24. This doctor knife allows only a thin layer of color coating to be applied to the cloth, and it will be evident from an inspection of the figure that the highest parts 26 of the embossed patterns will receive little or no coloring material. Those scores or shade lines 12 perpendicular to the edge of the doctor knife will, however, receive considerable of the coating material, while those scores 16 at an angle to the blade of the knife will receive less in proportion to their angularity, while those scores 14 which are parallel to the edge of the blade 24 will receive merely a slight deposit of the coating material 18.

The shade itself being translucent will allow the passage of light therethrough even though the coating material 18 has been applied, and as this is of varying degrees of thickness in its deposits upon the cloth, it will be evident that varying amounts of light will pass through the cloth when the same is in position against a window or the like. Accordingly, a very attractive and delightful two-tone or more color effect is produced, the same being outlined by the patterns themselves, thereby resulting in a very novel, decorative, and useful article.

I am aware that many changes may be

made and numerous details of construction varied throughout a wide range without departing from the principles of this invention, and I therefore do not propose limiting the patent granted hereon otherwise than as necessitated by the prior art.

5 I claim as my invention:

10 1. A two-tone window shade cloth having a pattern formed by embossed lines, and a colored coating of varying degrees of thickness in the said embossed lines, the angle of the lines with respect to the edge of the cloth determining the amount of coloring material.

15 2. A varicolored window shade cloth having patterns formed of lines indented into the material of the cloth, certain of said lines being indented deeper than others and forming the main pattern outlines, and certain other of said lines comprising groups of parallel 20 grooves arranged at different angles with respect to each other and with respect to the edge of the cloth.

25 3. A varicolored window shade cloth having patterns formed of lines indented into the material of the cloth, certain of said lines being indented deeper than others and forming the main pattern outlines, and certain other of said lines comprising groups of parallel 30 grooves arranged at different angles with respect to each other and with respect to the edge of the cloth, and a colored coating in the indentations.

35 4. A varicolored window shade cloth having patterns formed of lines indented into the material of the cloth, certain of said lines being indented deeper than others and forming the main pattern outlines, and certain other of said lines comprising groups of parallel 40 grooves arranged at different angles with respect to each other and with respect to the edge of the cloth, and a colored coating applied to said indentations, the depth of said 45 indentations determining the relative deposit of coloring material.

50 5. A varicolored window shade cloth having patterns formed of lines indented into the material of the cloth, certain of said lines being indented deeper than others and forming the main pattern outlines, and certain other of said lines comprising groups of parallel 55 grooves arranged at different angles with respect to each other and with respect to the edge of the cloth, and a colored coating applied to said indentations, those indentations parallel to the edge of the cloth having a greater quantity of coating material.

60 6. A process of manufacturing two-tone window shade cloth including the preliminary application, of a relatively flexible neutral-colored translucent coating to a cloth base, embossing the coated cloth, and the later application of a colored coating to the embossed cloth.

65 7. A process of manufacturing two-tone window shade cloth including the prelimi-

nary application of a relatively flexible neutral-colored translucent coating to a cloth base, embossing the coated cloth, and the later application of a colored coating to the embossed cloth, the depth and angularity of the indentations determining the relative translucency and pigmentation of the product.

70 In testimony whereof I affix my signature.

GEORGE M. JACKSON.
